CLAIM

The ornamental design for a mobile power device as shown and described.

DESCRIPTION

FIG. 1 is a first perspective view of a first embodiment of a mobile power device showing my design;

FIG. 2 is a second perspective view of the first embodiment thereof;

FIG. 3 is a front view of the first embodiment thereof;

FIG. 4 is a rear view of the first embodiment thereof;

FIG. 5 is a left-side view of the first embodiment thereof;

FIG. 6 is a right-side view of the first embodiment thereof;

FIG. 7 is a top plan view of the first embodiment thereof;

FIG. 8 is a bottom plan view of the first embodiment thereof;

FIG. 9 is a perspective view of another state of the first embodiment thereof;

FIG. 10 is a first perspective view of a second embodiment of a mobile power device showing my design;

FIG. 11 is a second perspective view of the second embodiment thereof;

FIG. 12 is a front view of the second embodiment thereof;

FIG. 13 is a rear view of the second embodiment thereof;

FIG. 14 is a left-side view of the second embodiment thereof;

FIG. 15 is a right-side view of the second embodiment thereof;

FIG. 16 is a top plan view of the second embodiment thereof; and,

FIG. 17 is a bottom plan view of the second embodiment thereof.

The broken lines are included for the purposes of illustrating portions of the mobile power device that form no part of the claimed design.
